Maxwell E. Spivack
ATTORNEY

UNITED STATES PATENT OFFICE

ANNA KOTLER, OF NEW YORK, N. Y.

WINDOW

Application filed September 12, 1929. Serial No. 392,144.

This invention relates to improvements in the construction of windows as used in dwelling houses, office buildings and similar structures.

Ordinarily windows consist of a frame or casing having channels in its inner sides to slidably receive outer and inner balanced sashes provided with transparent panels for the passage of light, these panels requiring frequent cleaning.

10 Although the inner facing surfaces of the sashes are commonly easy of access, their outer surfaces are reached with difficulty by window seats, ladders and other like devices, or by leaning outwardly through the partially opened window, all of which is inconvenient and unsafe.

It is therefore, an object of the present invention to provide a window sash having an auxiliary sash, in which the glass of a window or the like is set and retained, pivotally arranged and adapted to swing with relation to the sash.

A further object is to provide a sash having an outer and an inner frame and co-operative means in the outer and inner frames whereby the inner frame is adapted to be pivoted and slid with relation to the outer frame.

A further object is to provide a window sash so hung as to permit turning on a vertical axis whereby either side is rendered accessible.

A further feature is in the provision of means whereby both sashes may be opened simultaneously.

It is a further object of this invention, to construct a window having an outer and an inner frame wherein the inner frame can be slid along channels in the upper and lower members from one end of the opening in the outer frame to the other end of the outer frame, and freely swung laterally at any point along the channels, and wherein the inner frame may be completely reversed or turned inside out and completely confined in reversed position within the outer frame.

These and other such objects as neatness in appearance, ease of manipulation and ready substitution for the common type of sash, are accomplished by the novel construction, com-

bination and arrangement of parts herein-after described and shown in the accompanying drawing, constituting a material part of this disclosure, and in which:

Figure 1 is a front elevational view of a conventional type of window casing showing a pair of sashes made in accordance with the invention installed therein.

Figure 2 is an enlarged cross sectional view taken on line 2—2 of Figure 1.

Figure 3 is a sectional view taken on line 3—3 of Figure 1.

Figure 4 is another like sectional view taken on line 4—4 of Figure 1.

Figure 5 is a fragmentary side view showing a modification in construction.

Figure 6 is a similar corner view showing a further modification in construction.

The casing shown is in all respects of the usual type of construction, comprising a pair of spaced jambs 10 connected by a lintel 11 at their tops and a sill 12 at the bottom.

Both jambs are channelled at their proximate inner surfaces or provided with parting strips 13—13'—13'' to produce grooves 14—15 in which are slidably received sash frames 16—17, respectively top and bottom.

Each sash comprises an outer and inner frame which are, in the embodiment shown, regular rectangles adapted to take the place of common sashes for which they may be substituted. The outer frames have at their inner edges inreaching flanges, as at 16'.

The inner surfaces of the upper and lower elements of the outer frame are grooved longitudinally to receive channel guides 18 having horizontal flanges 18' held by fastenings in fixed positions on the frame.

The inner frame 19, in which is fixed a transparent plate 20, as glass, is fitted to slide in the channel 18 and pivot or swing by trunnions 21 extending into the channels 18.

The upright member 19' of the glazed inner frame 19 is preferably rounded on its outer longitudinal edge and set centrally of its length therein is a socket 23 while a similar socket 24 is disposed in the opposite, front member of the inner frame.

Fixed in the front surface of the outer frame 16 in both of its upright elements, are

sheet metal casings 25—26, carrying bolts 27—28 provided with knobs accessible from the front of the casings and urged into engagement with the sockets by coiled compression springs as shown.

Fixed in each side of the front member of each inner frame are knobs 29—29' by which the glass panels may be conveniently manipulated.

10 Figure 5 is a fragmentary side view of a modification in construction showing the elements of the outer frame grooved near one of its sides to receive the short channel guides 18".

15 Figure 6 is a corner view of a further modification in construction showing the trunnions 21 in the inner frame 19, extending in metal sockets 22, set in the upper and lower members of the outer frame 16.

20 During the summer it frequently is desirable to have a window wide open and at the same time screening the open space to prevent flies and insects from entering the room. By my invention a screen can be placed adjacent the window and the latter opened full without displacing or removing the screen.

From the foregoing it will be seen that the inner frame may be securely locked within the outer frame at will or released to pivot and slide on its trunnions thus exposing both sides of each inner sash frame whenever desired.

25 It is also to be noted that both of the inner frames may be opened simultaneously, thus presenting a greater air space than can be obtained by sashes which merely slide.

30 It is also to be noted that in constructing a window in accordance with my invention, not only can the inner frame be slid along the channels from one end of the opening in the outer frame to the other end and freely swung laterally at any point along the channels, but the inner frame can be completely reversed or turned inside out and completely confined 35 within the outer frame, which is an advantage, for instance, in cold weather, when one desires to prevent drafts in the room while cleaning the window.

35 While certain preferred embodiments of this device have been shown and described, it will be understood that changes in the form, arrangements, proportions, sizes and details thereof may be made without departing from the scope of the invention as defined in the appended claims.

Having thus described my invention, what I claim as new and desire to secure by Letters Patent is:—

40 1. A window sash comprising a rigid outer frame, metal channels secured in the top and bottom members thereof, an inner frame having pivots in its top and bottom members to enter said channels, the side member of said inner frame being arcuately formed on the axis of said pivots, stops on the outer frame

limiting the closing movement of the inner frame, casings set in the outer frame, sockets in the inner frame opposite said casings, spring actuated bolts in said casings to engage said sockets when said frames are in closed relations, and means carried by the inner frame to facilitate manipulation. 70

2. A window sash comprising a rigid outer frame, metal channels secured in the outer frame, an inner frame having pivots adapted to enter said channels, the side member of said inner frame being arcuately formed on the axis of said pivots, stops on the outer frame limiting the closing movement of the inner frame, casings set in the outer frame, sockets in the inner frame opposite said casings to engage said sockets when said frames are in closed relations, and means carried by the inner frame to facilitate manipulation. 75

3. A window sash comprising an outer frame, metal channels secured in the top and bottom members thereof, an inner frame having pivots engaged in said channels, said member being rounded throughout its length on the axis of said pivots, flanges on said outer frame against which the inner frame contacts when closed, spring actuated bolts set in said outer frame, and metal sockets in the inner frame to receive said bolts. 80

4. A window comprising an outer frame, metal channels secured in the frame, an inner frame having pivots engaged in said channels, flanges on said outer frame against which the inner frame contacts when closed, said inner frame being adapted to be swung freely, laterally at any point along the channels and contact against the said flanges in complete reversed position and means to retain said inner frame when in juxtaposition to said outer frame. 95

5. A window comprising an outer and an inner frame, channels in the upper and lower members of the outer frame, means on the inner frame to engage the channels by which the inner frame may be slid along the channels and freely swing laterally at any point along the channels, said inner frame being adapted to be completely reversed and completely confined in reversed position within the outer frame. 100

Signed at New York, in the county and State of New York, this 10th day of September, 1929.

ANNA KOTLER.
